UNITED STATES PATENT OFFICE

2,229,930

CABINET CONSTRUCTION

Earl E. Nofzinger, Greenville, Mich., assignor to
Gibson Electric Refrigerator Corporation, a cor-
poration of Michigan

Application December 7, 1939, Serial No. 308,057

5 Claims. (Cl. 41—35)

This invention relates to improvements in cabinet construction and more especially heat insulated cabinets made of sheet metal and adapted for use as refrigerators, stoves and the like.

Such cabinets are frequently made of panels, or sections joined together to form a unit. A customary way of joining the panels is to bend the adjacent edges inwardly and fasten them together in any suitable manner as by welding, bolting, or the like. One of the features of my invention is the provision of means for concealing the crevice between two panels thus joined.

Besides being useful in concealing a crevice or crack where panels are joined, my invention has a wider application for use in connection with concealing or covering any kind of crack or crevice; and, in fact, not only conceals the crack or crevice but also adds to the appearance of the object by forming a raised line which may be of any suitable color and thus take the place of decoration. In fact, if the decorative feature alone is desired, there may be no crack or crevice at all; but the invention may be employed solely for the purpose of adding a decorative mark or line. This method of lining or marking articles will be found to be much more durable and also cheaper than painting. Such a line can be put on much more straightly by the practice of my invention than by painting.

This application is a continuation-in-part of my copending application Serial No. 277,549 filed June 5, 1939.

In general, my invention contemplates the use of a spiral spring or wire stretched over the crack. The wire or spring may be bare or enclosed within extruded plastic material or cement. In the event the invention is used for decoration only, there may be provided a groove in the sheet metal in which the spring or wire, coated or uncoated, is laid.

In those forms of devices embodying the features of my invention, shown in the accompanying drawing—Fig. 1 is a vertical sectional view of the top of a cabinet, for example a refrigerator cabinet or the like, Fig. 2 is a view taken as indicated by the line 2 of Fig. 1, Fig. 3 is a detail view showing the spring taken as indicated by line 3 of Fig. 4, Fig. 4 is a view taken as indicated by line 4 of Fig. 3, Fig. 5 is a view of a modification taken as indicated by the line 5 of Fig. 6, Fig. 6 is a view taken as indicated by the line 6 of Fig. 5, Fig. 7 is a view of another modification taken as indicated by the line 7 of Fig. 8, Fig. 8 is a view taken as indicated by the line 8 of Fig. 7, Fig. 9 is a view of another modification taken by the

line 9 of Fig. 10, Fig. 10 is a view taken as indicated by the line 10 of Fig. 9, and Fig. 11 is a vertical sectional view of another modified form.

As shown in the drawing, 10 and 11 indicate the upper portions of preformed metallic side panels, one for each of the side walls. 16 indicates a top sheet. The adjacent edges of the sheets are provided with inwardly turned flanges 10^f and 16^f respectively which may be fastened together by welding or any other suitable means. 10^f indicates a coiled wire spring slightly under tension lying over the crevice at the top where the top sheet 16 is joined to the side sheets or panels 10 and 11. It will be seen that when the inwardly turned edges on the adjacent sheets are joined together there will be left a small crevice on the outside. The spring 10 slightly under tension is put over this crevice and may be left bare as shown in Figs. 3 and 4, or filled with any suitable substance like plastic material or cement as indicated by 71 in Figs. 5 and 6. This makes a neat appearing protective covering for the crevice. The spring may be held in position in any suitable manner. For example, as here shown, the ends of the spring are straightened and hooked over the flanges of the metal on the inside as indicated by 72.

I have found it preferable to make the material 71 extruded plastic material which hardens either before or after the spring is applied. Any decorative coloring may be given to the material.

Instead of using a spring, a stranded wire (plastic, braided, or otherwise formed), cable, single wire or other suitable tension member may be employed. For example, in Figs. 7 and 8 I have shown a bare wire cable indicated by 73 instead of a spiral spring. In Figs. 9 and 10 I have shown such a cable 73^a coated with plastic material 74. I have found, for example, that a stranded wire having a diameter of substantially $\frac{3}{2}$ of an inch with a coating of "Tenite" extruded over it may be employed. The overall diameter would be from $\frac{1}{2}$ to $\frac{3}{2}$ inch. By the use of this plastic material over the steel cable it is possible to stretch it tightly in the seam fastening both ends securely. This will give the necessary flexibility and the "Tenite" can be furnished in any color which might be desired for the best appearance.

In Fig. 11 I have shown a similar steel cable 73^a coated with plastic material 74 used for decorative purposes only. As here shown, there is no crack or crevice. The sheet metal 75 is merely provided with a groove 76 where the decorative marking line is desired and the plastic- 55

coated cable is laid in this groove. In this manner, a raised decorative colored (if desired) stripe may be placed on sheet metal in a simple accurate, effective and cheap manner.

5 As stated above "Tenite" has the necessary flexibility and even after it hardens it retains sufficient flexibility so that it is not likely to be broken by impact of hard objects. Likewise, it is contemplated that the plastic material used 10 in the spring shall permanently retain sufficient flexibility after it hardens so that it is not likely to be chipped or broken. Such flexibility is not necessarily utilized to permit bending of the strip after it has been permanently installed, as, in 15 most cases, there will be no occasion for such bending. What is meant by flexibility, particularly as the term is here used, is that the strip even after it has hardened shall have sufficient plasticity, resiliency, elasticity, or softness so that 20 it can stand considerable abuse, as by impact with hard objects, without chipping, breaking, or cracking.

While there are shown and described certain 23 embodiments of the invention, it is to be understood that it is capable of many modifications. Changes, therefore, in the construction and arrangement may be made without departing from the spirit and scope of the invention as disclosed

in the appended claims, in which it is intended to claim all novelty inherent in the invention as broadly as permissible, in view of the prior art.

What I claim as new, and desire to secure by Letters Patent, is:

5 1. In a cabinet of the character described having two sheets of metal with their adjacent edges turned inwardly and joined together leaving a crevice on the outside, a coil spring filled with cement lying over said crevice.

10 2. In a cabinet of the character described having two sheets of metal with their adjacent edges turned inwardly and joined together leaving a crevice on the outside, a coil spring filled with flexible plastic material lying over said crevice.

15 3. In a cabinet of the character described having two sheets of metal with their adjacent edges turned inwardly and joined together leaving a crevice on the outside, a tension member coated with plastic material lying over said crevice.

20 4. In a sheet metal construction, a groove with a tension member coated with plastic material lying therein.

25 5. A raised strip of flexible plastic material on a substantially flat surface held in position by a tension member embedded in said plastic material.

EARL E. NOFZINGER.
